CARBURETTOR BODY

Geoffrey Hartshorne, Shenstone, England, assignor to
AMAL Limited, Birmingham, Warwickshire, England

Filed June 27, 1972, Ser. No. 266,730

Claims priority, application Great Britain Jan. 5, 1972

Term of patent 14 years

Int. Cl. D15—01

U.S. Cl. D77—1 A

FIGURE 1

FIGURE 2

FIGURE 3

FIGURE 4

FIGURE 5

FIGURE 6

FIG. 1 is a top plan view of a carburetor body showing my new design;

FIG. 2 is a bottom plan view thereof;

FIG. 3 is a rear elevational view thereof;

FIG. 4 is a side elevational view thereof;

FIG. 5 is a front elevational view thereof;

FIG. 6 is a side elevational view thereof, opposite to that shown in FIG. 4.

I claim:

The ornamental design for a carburetor body, as shown.
